(57) **CLAIM**

The ornamental design for a refrigerator module for a vehicle as shown and described.

DESCRIPTION

FIG. 1 is a perspective view of a refrigerator module for a vehicle, showing our new design.

FIG. 2 is a front elevational view thereof.

FIG. 3 is a left side elevational view thereof.

FIG. 4 is a right side elevational view thereof; and,

FIG. 5 is a top plan view thereof.

Stippling in the drawings represent the three-dimensional contours of the design, and is not intended to indicate surface decoration. The broken lines shown in the drawings depict portions of the refrigerator module for a vehicle that form no part of the claimed design.
